UNITED STATES PATENT OFFICE.

LOUIS PETO, OF VESTABURG, PENNSYLVANIA.

PIPE BENDER.

Application filed January 31, 1923. Serial No. 616,145.

To all whom it may concern:

Be it known that I, Louis Peto, a citizen of Czechoslovakia, residing at Vestaburg, in the county of Washington and State 5 of Pennsylvania, have invented certain new and useful Improvements in Pipe Benders, of which the following is a specification.

This invention relates to improvements in pipe benders of the three-point jack type.

10 An important object of the invention is to provide a pipe bender of a portable nature that is suitable for plumbers or electricians while working away from their home shop.

15 A further object of the invention is to provide an extremely durable and efficient device for this purpose which may be adapted to pipes of a wide range of sizes.

Other objects and advantages of the invention will be apparent during the course 20 of the following description.

In the accompanying drawing forming a part of this specification and in which like numerals are employed to designate like 25 parts throughout the same,

Figure 1 is a top plan view of the device embodying this invention,

Fig. 2 is a side elevational view, partly 30 in section, taken on lines II—II of Fig. 1, and

Fig. 3 is a fragmentary end elevational view, partly in section, taken on lines III—III of Fig. 1.

In the drawing, wherein for the purpose 35 of illustration is shown a preferred embodiment of this invention, the numeral 5 designates a substantially U-shaped frame that is constructed of any strong and rigid metal and embodies parallel spaced side arms 6 that are joined at their inner ends 40 by the cross piece 7. The outer free ends of the side arms 6 are bent upwardly at 8 and formed with an arcuate pocket 9 upon their inner vertical faces. Longitudinally 45 extending slots 10 are formed in the side arms 6 for receiving guiding means associated with the moving jaw which will be described hereafter. The cross piece 7 is provided with a boss 11 that is formed integrally therewith and extends at right 50 angles therefrom. This boss is provided with a transverse squared opening 12 and a threaded opening 13 that are provided for accommodating portions of the movable 55 jaw.

The movable jaw embodies a head portion

14 that is provided with an arcuate pocket 15, as best shown in Fig. 2, and a squared guide arm 16 that is adapted to slidably engage the square opening 12 formed in the 60 boss 11. Extending transversely through the head 14 is a cross arm 17 that extends laterally in opposite directions to terminate beyond the side arms 6. The outer ends of this cross arm 17 are each provided with 65 a link member 18 that extends through the slots 10 formed in the said arms 6. The free ends of these link members are each provided with a headed pin or screw 19 that is adapted to carry roller members 20, as 70 best shown in Fig. 3. It is to be understood that these link members 18 are provided for guiding the movement of the head member 14 and the roller members 20 will prevent binding of the said link members. There is further provided a forcing 75 screw 21 that is threaded through the opening 13 formed in the boss 11 and is provided with a squared head 22 that is adapted to be engaged by a wrench or the like 80 for turning the said screw. The inner end 23 of this forcing screw is adapted to engage within a socket 24 formed in the head 14, as best shown in Fig. 2.

In employing the device to bend a pipe, 85 the said pipe section is placed into engagement with the arcuate pockets 9 formed in the upwardly bent ends 8 of the spaced side arms 6 and the arcuate pocket 15 formed in the movable head 14 is brought into engagement with the pipe section by actuating the screw 21. It will readily be seen that by further turning the screw 21 the movable head 14 will be forced between the upwardly 90 bent ends 8 of the side arms 6 and will therefore bend or curve the said pipe section. The movable head portion 14 will be guided in its movement by the squared arm 16 that extends through the boss 11 and will be prevented from shifting laterally by the engagement of the link members 18 with the walls of the slots 10 formed in the side arms 6. It is to be understood that these link members 18 are rigidly connected with the cross arm 17 which is in turn rigidly connected with the head portion 14, and that the manner of forming these rigid connections is not shown as it does not enter into 105 the scope of the invention.

It is to be understood that the form of 110 this invention herewith shown and described is to be taken as the preferred em-

bodiment of the same, and that various changes in the shape, size, and arrangement of parts may be resorted to without departing from the spirit of the invention or the 5 scope of the subjoined claims.

Having thus described the invention, I claim:—

1. In a device of the character described, a U-shaped frame embodying spaced side 10 arms having longitudinally extending slots formed therein, a cross piece connecting said arms, a boss formed on said cross piece, and upwardly bent ends formed on said arms, a movable head supported by said boss, a 15 cross arm carried by said head, a link member carried by each end of said cross arm, said link members projecting through the slots formed in said arms, pins carried by the free ends of said link members, rollers 20 carried by said pins, and means carried by said boss for moving said head toward the upwardly bent ends formed on said side arms.

2. In a device of the character described, a U-shaped frame embodying spaced side 25 arms having longitudinally extending slots, a cross piece connecting the inner ends of said arms, an upwardly extending boss formed on said cross piece, and upwardly extending hook-shaped ends formed on said 30 arms, a movable jaw embodying a head having an arcuate pocket formed in its outer end and a guide arm extending through an opening formed in said boss, a cross arm carried by said head, a depending member carried by each end of said cross arm and projecting through said longitudinal slots, means carried by the lower ends of said depending members adapted to anti-frictionally engage the lower surfaces of said side 35 arms, and a feed screw threadedly engaging said upwardly extending boss and loosely engaging said head for moving the latter toward said hook-shaped ends.

In testimony whereof I affix my signature.
LOUIS PETO.
